UNITED STATES PATENT OFFICE

153,033

DESIGN FOR A CONTAINER FOR WASHING
FABRIC ARTICLES OR THE LIKE

Arthur J. Rochow, Pittsford, N. Y.

Application October 23, 1946, Serial No. 134,183

Term of patent 14 years

(Cl. D49—1)

To all whom it may concern:

Be it known that I, Arthur J. Rochow, a citizen of the United States, residing at Pittsford, in the county of Monroe and State of New York, have invented a new, original, and ornamental Design for Container for Washing Fabric Articles or the like, of which the following is a specification, reference being had to the accompanying drawings, forming part thereof.

Fig. 1 is a side elevation of a container for washing fabric articles or the like showing my new design;

Fig. 2 is a top plan view thereof;

Fig. 3 is a view similar to Fig. 1 but viewed from a different side, and

Fig. 4 is an enlarged partial sectional view shown on line 4—4 of Fig. 1.

I claim:

The ornamental design for a container for washing fabric articles or the like, substantially as shown.

ARTHUR J. ROCHOW.
